UNITED STATES PATENT OFFICE.

WARREN W. DOHERTY, OF NEW YORK, N. Y., ASSIGNOR TO ELDON E. COONRADT, OF YONKERS, NEW YORK.

MUFFLER CUT-OUT.

1,178,500.

Specification of Letters Patent. Patented Apr. 11, 1916.

Application filed May 26, 1915. Serial No. 30,641.

To all whom it may concern:

Be it known that I, WARREN W. DOHERTY, a citizen of the United States, residing at New York, in the county of New York, State of New York, have invented certain new and useful Improvements in Muffler Cut-Outs; and I do hereby declare the following to be a full, clear, and exact description of the invention, such as will enable others skilled in the art to which it appertains to make and use the same.

This invention relates to improvements in muffler cut-outs, and is adapted for use in connection with the exhaust pipes of explosive engines although the device is not restricted to this particular use.

The object of the invention resides in the provision of a muffler cut-out which will be exceedingly simple in construction, embody 20 comparatively few parts, be cheap to manufacture, and at the same time will be efficient and reliable in use.

With the above and other objects in view the invention consists in the details of construction and in the arrangement and combination of parts to be hereinafter more fully described and particularly pointed out in the appended claim.

In describing the invention in detail reference will be had to the accompanying drawings wherein like characters of reference denote corresponding parts in the several views, and in which—

Figure 1 is a longitudinal section of a muffler cut-out with the parts in the position they would occupy when the exhaust gases are passing through the muffler; Fig. 2, a view similar to Fig. 1 with the parts in the position they would occupy when the cut-out has been operated to prevent the passage of gases through the muffler; Fig. 3, a section on the line 3—3 of Fig. 1, and Fig. 4, a perspective view of the valve employed in the cut-out.

Referring to the drawings the improved cut-out is shown as comprising a tubular member A including cylindrical terminal portions 10 and 11 and an intermediate portion 13 of substantially square cross sections 50 and having an opening 14 in one side and the opposite side arched longitudinally as at 15 for the purpose of permitting free pivotal movement of the valve member of the cut-out to be hereinafter referred to. Formed 55 on opposite sides of the intermediate portion

13 at one end of the opening 14 are alined bearings 16 the centers of which constitute the center of the curve traced by the arched portion 15. The cylindrical portions 10 and 11 have the outer ends of their bores enlarged as at 17 and engaged in these enlarged portions of said bores are exhaust pipe sections 18 which are held in assembled relation to the member A through the medium of set screws 19 mounted in the portions 10 and 11 respectively. 60

The valve employed in the cut-out is formed of a tubular member B having parallel opposite sides 20 and curved opposite sides 21 and 22, said sides 21 and 22 being 70 oppositely curved as clearly shown in the drawing. The opposite sides 20 are connected by a tubular portion 23. The opposite sides 20 are provided respectively with flanges 24, while the free end of the side 21 is provided with an extension 25. One wall of the opening 14 is provided with an inwardly directed stop flange 26 while the inner end of the tubular portion 11 is provided with a stop flange 27. In assembling the 80 valve B within the member A the tubular portion 23 is alined with the bearings 16 and a shaft 28 inserted through the bearing and the tubular portion and secured to the latter by means of pins 29. An operating lever 30 85 is fixed on the shaft 28 exteriorly of the member A. Encircling the shaft 28 exteriorly of the member A is a helical spring 31 one end of which is anchored to the member 90 A and the other end to the lever 30. This spring constantly tends to hold the valve B in the position shown in Fig. 1. In this position one edge of the side 22 of the valve engages the stop flange 27 and the exhaust gases are free to pass through the cylindrical portion 17, through the valve B and through the cylindrical portion 17 to the muffler (not shown). It will be noted that 95 when the valve B is positioned to permit the passage of exhaust gases to the muffler the flanges 24 will engage the lower edges of the sides of the intermediate portion 13, while the flange 25 will engage the stop flange 26. The valve B is operated to the position 100 shown in Fig. 2 through the medium of suitable connections with a foot lever conveniently disposed for actuating by the driver. When the valve B is in the position shown in Fig. 2 the side 22 closes communication 105 between the cylindrical portions 10 and 11 110

and engages the stop flange 26. In this position the exhaust gases will pass out through the opening 14 and will be directed by the side 21 of the valve so as to partake of a course substantially parallel to the roadway and thus do away with the unpleasantness of dust that would arise should the exhaust gases take a course directly downward.

What is claimed is:—

- 10 In a muffler cut-out the combination of a tubular member having an opening in one side, and a valve pivoted in said member and adapted to move through said opening, said

valve including spaced walls, one of said walls closing the opening in the member 15 when the valve is moved to its limit in one direction and the other of said walls closing the bore of the member when the valve is moved to its limit in the other direction.

In testimony whereof, I affix my signature, in the presence of two witnesses.

WARREN W. DOHERTY.
